Primary Examiner — Paula Allen Greene(74) *Attorney, Agent, or Firm* — Patterson & Sheridan,
LLP(57) **CLAIM**

The ornamental design for a headphone, as shown and described.

DESCRIPTION

FIG. 1 is a perspective view of a headphone according to our design;

FIG. 2 is a front view of the headphone shown in FIG. 1;
FIG. 3 is a back view of the headphone shown in FIG. 1;
FIG. 4 is a right side view of the headphone shown in FIG. 1;FIG. 5 is a left side view of the headphone shown in FIG. 1;
FIG. 6 is a top view of the headphone shown in FIG. 1; and,
FIG. 7 is a bottom view of the headphone shown in FIG. 1.
The broken lines depict environment that forms no part of
the claimed design.**1 Claim, 5 Drawing Sheets**| (56)	References Cited
